UNITED STATES PATENT OFFICE.

JONATHAN P. FERRENBURG, OF NEW MADRID, MISSOURI.

SHINGLE-MACHINE.

SPECIFICATION forming part of Letters Patent No. 290,222, dated December 18, 1883.

Application filed October 15, 1883. (No model.)

To all whom it may concern:

Be it known that I, JONATHAN P. FERRENBURG, a citizen of the United States, residing at New Madrid, in the county of New Madrid and State of Missouri, having invented certain new and useful Improvements in Shingle-Machines; and I do hereby declare that the following is a full, clear, and exact description of the same, reference being had to the annexed drawings, making a part of this specification, and to the letters and figures of reference marked thereon.

Figure 1 of the drawings is a side elevation of my improved shingle-machine, partly in longitudinal section, and showing it connected to the driving mechanism. Fig. 2 is a perspective view of the machine; Fig. 3, a perspective view in longitudinal section.

The present invention has relation to certain new and useful improvements in machines for cutting shingles; and the object thereof is to improve the machine in the several details of construction, whereby the operation of cutting the shingles is rendered more simple and practicable, and enabling the shingles to be cut from the block and completed with great rapidity, the shingles being rived and automatically placed in position to be shaved, thus completing the operation without the necessity of handling the shingle after being cut from the block. These several objects I attain by the construction substantially as shown in the drawings and herein-after described and claimed.

In the accompanying drawings, A represents a rectangular frame of any suitable construction, having upon its interior longitudinal grooves to receive the sides *a* of a carrier, B, which is in form of a skeleton frame. This carrier B receives the wooden block from which the shingles are to be cut, said block resting on and being supported by the stationary platform C. The carrier B is caused to have a horizontal reciprocating motion lengthwise of the frame A, the sides *a* of the carrier located in the grooves upon the interior sides of the frame guiding the carrier in its movement. The forward end of the carrier B is of less depth or thickness than the rear portion of the carrier, so that a portion of the front edge of the wooden block will be exposed

to the action of the cutting-edge of a stationary knife, D, as the block is forced against it by the forward motion of the carrier. This knife D is arranged crosswise or transversely of the frame A, its ends being supported in the sides thereof, and above its ends are located spiral or rubber springs *b*, their tension regulated by set-screws or other means usually employed for the purpose. By this means the knife D is given a yielding motion of any necessary degree to conform to the irregularities in the wooden block. Every time the block is forced against the knife it cuts therefrom a piece from which the shingle is made in the completion of the operation. The piece, as it is cut from the block, passes down in contact with a knife, E, which is permanently attached to a horizontal sliding frame, F, having its guides in the sides of the frame A. This frame F, as it passes in an opposite direction to the forward motion of the carrier B, will cause the knife E to be forced against the piece already cut from the block, severing it in two pieces. As the frame E passes forward in an opposite direction it will crowd the lower half of the piece last cut between the knives G, which commences at the butt of the shingle and shaves both sides at once, tapering toward the top thereof.

The frame F is provided with dividing-bars *d*, extending forward and between the knives G to the end of the plate H, and are formed tapering as they pass between the knives, so that it will admit of the latter coming nearer together, and thus make an angular cut to give to the shingle the proper slope.

It should be understood that the frame F makes two motions forward and back, while the carrier B makes one motion. Thus it will be seen that the two pieces last cut, which are to form the shingles, are completed as rapidly as the pieces are cut from the block by the knife D.

The extremities or ends of the knives G project through and beyond the sides of the frame A, and are kept pressed against the dividing-bars *d* by suitable springs, preferably of rubber, as shown at *e*. To the ends of these knives G are secured wire braces *f*, which are in turn connected to the sides of the frame A by screws or other suitable means, and, if de-

sired, set-screws may be employed as an additional means, both above and below the projecting ends of the knife-bars or knives G, to retain them in proper working position.

5 The several knives are composed of steel, and the knife E has sufficient elasticity to spring up or yield in case of the shingles splitting thick, and, if desired, may be adjustable to increase or diminish its height, said adjustment being preferably made by set-screws or any of the usual means.

The frame F, at its forward end, has connected to it a plate, I, and, like the plate H, extends the entire width of the frame A, the knife E 15 immediately adjoining the inner edge thereof, as more clearly shown in Fig. 3.

To the under side of both the plates H I are connected spring-guides K, which consist of curved plates having interposed between them 20 and the plates H I spiral or other suitable springs, so that the curved plates will yield, but bear against the shingle sufficiently to hold it in proper position when passing under the guides.

25 A platform, L, is connected to the sides of the frame A in such manner as to have a yielding motion when required, the front end of platform resting on spiral or rubber springs g. The front of the platform L or the outer edge 30 thereof is on the same horizontal plane with the cutting-edge of the lower one of the knives G, said platform supporting the shingle, and the pressure thereon of the guides K holding it in position while it passes between the 35 knives.

The knife D, if found preferable, may be so supported in the sides of the frame by set-screws or any other well-known means that will admit the height of the knife being ad- 40 justed.

The machine may be made of any suitable material, either wood or metal, or both, and is supported by a suitable frame, M, at the required height.

45 The means which I preferably employ to impart to the frame F and carrier B the necessary vibratory or reciprocating motion is as follows: A large pulley, N, over which passes the belt h, extending to the driving-power, is mounted upon a transverse shaft, i, and keyed thereto, so that said shaft will move with it. This shaft has its bearings in suitable boxes connected to the frame M, and has keyed to it a gear-wheel, P, the teeth of 50 which mesh with those of a larger gear-wheel, R, arranged above it. The shaft i has connected to it a crank-arm, k, with a pin, l, which latter enters the slot in an arm, m, connected to the frame F.

60 To the hub of the gear-wheel R is a crank, n, connection being made with the carrier B by a pitman, p, pivoted thereto and to the crank, as shown in Fig. 1. The gear-wheel R has twice the circumference as the wheel P, 65 so that at one complete revolution of the former the latter will make two complete revo-

lutions, thereby, as the carrier has finished its movement forward and returned, the frame F will have moved twice as fast and completed two of such motions; or, in other words, the 70 carrier will have one motion only to the frame's two motions.

Having now fully described my invention, what I claim as new, and desire to secure by Letters Patent, is—

75 1. In a shingle-machine, the combination, with a longitudinally-reciprocating carrier and a stationary platform arranged under it to support the shingle-block while it is being carried forward, of a knife supported transversely in the frame of the machine, and having suitable springs arranged above it to give to said knife the necessary yielding motion to adjust itself to the varying inequalities of the block, substantially as and for the purpose set 80 forth.

2. In a shingle-machine, the combination, with a longitudinally-reciprocating carrier, a stationary platform arranged under it, and a knife supported transversely in the frame of 85 the machine, and provided with springs to give it a yielding motion, of a plate arranged forward of the carrier, and having upon its underside suitable spring-guides, substantially as and for the purpose specified.

95 3. In a shingle-machine, a longitudinally-reciprocating carrier, a platform arranged under the same, and a transverse knife against which the block is forced by the carrier, in combination with a longitudinally-reciprocating frame located under the carrier and platform, and provided with a knife to operate in connection with the knife above it, substantially as and for the purpose set forth.

100 4. In a shingle-machine, the combination, with a longitudinally-reciprocating frame carrying a transverse knife, of two stationary knives and dividing-bars passing between them, and connected to the movable frame, substantially as and for the purpose specified.

105 5. In a shingle-machine, the combination, with two stationary knives, arranged one above the other, of a longitudinally-reciprocating frame carrying a knife, dividing-bars which pass between the stationary knives, and a 110 plate provided upon its underside with spring-guides, as set forth.

115 6. In a shingle-machine, a longitudinally-reciprocating frame carrying a knife, of a yielding platform arranged under the forward part of the movable frame, and stationary knives, arranged one above the other, between which the shingle passes, substantially as and for the purpose specified.

120 7. In a shingle-machine, a longitudinally-reciprocating carrier, a stationary knife arranged in front of the same, and a plate having spring-guides, in combination with a stationary platform arranged under the carrier, a longitudinally-reciprocating frame, carrying a knife and plate with spring-guides, and 125 dividing-bars passing between two stationary

knives arranged under said plate, substantially as and for the purpose described.

8. In a shingle-machine, the combination, with a longitudinally-reciprocating frame carrying a knife and dividing-bars, of two transverse adjustable knives, said bars being tapering and passing between the knives, substantially as and for the purpose set forth.

In testimony that I claim the above I have hereunto subscribed my name in presence of 10 two witnesses.

JONATHAN P. FERRENBURG.
